UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

CORRUGATED PLATE WITH INTEGRAL POST

Application filed September 24, 1928. Serial No. 308,104.

The invention relates to railway freight train cars and more particularly to corrugated plates with integral posts therefor having an integral strut-beam adjacent one or both side margins of a metallic plate, and the object of the invention is to reinforce such a strut-beam adjacent its middle portion which is its place of maximum bending moment under columnar or beam stresses.

Such a construction when used in house or roofed cars (such as box, automobile, stock, etc.,) would eliminate the use of corner post or door post, or if the strut-beam is positioned horizontally, would eliminate the use of the end plate or end sill. When used in open top cars (gondolas) the corner post could be dispensed with.

Another object of the invention is to form a wall of a railway car of two plates secured together along a horizontal line and to form an integral post adjacent each vertical margin thereof and to reinforce the connection between the two plates at each corner post.

In the drawings:

Fig. 1 shows a railway box car equipped with a typical application of my device.

Fig. 2 is a side elevation of Fig. 1.

Fig. 3 is a section on line 3—3 of Fig. 1.

Fig. 4 is a perspective view of a metallic plate wall having an integral corner post formed according to my invention.

Fig. 5 is an unsheared corrugated metallic plate.

The drawings show my invention applied to a railway box car wherein the metallic plate 1 forming the end wall of the car is provided with an integral Z shape member adjacent each of its opposite vertical margins, which members are secured to the upper side plates 2 and lower side sills 3, respectively, on each side of the car, thus forming the usual corner post, that is, the integral Z shape formation or members perform the functions of the usual corner post of the car. (This construction is disclosed and claimed in my co-pending application Serial No. 308,102, filed September 24, 1928.) Each Z shape member comprises a web 4, an outer flange 5 and inner flange 6. Such a Z shape member construction provides a very strong column to resist

stresses longitudinally of its length and furthermore such a Z shape construction forms a very efficient beam to resist stresses normal to its length. This statement is true where the stresses are parallel to the web 4, 55 normal to the web or diagonal thereto, therefore, such a Z formation forms a very efficient corner post construction.

When a member is subjected to columnar stresses or beam stresses the maximum fibre stress occurs adjacent the middle of the member and as the corner post (or in fact any post of a railway car) is subjected to both of such stresses, I prefer to reinforce the middle portion of the integral corner post as herein 60 described.

A great many car ends now in service have an upper and lower metallic plate secured together along horizontal lines having integral horizontal corrugations in each sheet. Such 70 sheets are secured along their vertical edges to the corner post of the car which extend continuously from sill to plate of the car. In forming a plurality of parallel corrugations 10 in a metallic sheet and terminating them 75 within the margins of the sheet, as at 11, the plate is drawn in adjacent its middle portion, as shown in Fig. 4, and it is customary to shear them along lines 12—12 and 13—13. Two of such plates are then secured together by a 80 lap joint and a single row of rivets 14.

When an integral corner post is formed in such a construction a weak place is formed where the two plates are secured together because a riveted connection is not as strong as 85 the other portions of the integral corner post, therefore, in my construction I shear the corrugated plates only along lines 13—13 so that when the two plates are placed together, the overlapping relation of the webs and the 90 outer flanges (and preferably also the inner flanges) is greater than elsewhere, thus giving a greater bearing area between the attached plates at the integral corner post than elsewhere and providing better means of securing the plates together than has heretofore been used. Furthermore, this increased overlapping relation between the plates reinforces 95 the integral post at its middle portion which is 100

the point of maximum bending moments for columnar or beam stresses.

The accompanying drawings illustrate the preferred form of the invention, though it is to be understood that the invention is not limited to the exact details of construction shown and described, as it is obvious that various modifications thereof within the scope of the claims will occur to persons skilled in the art.

10 I claim:

1. In a railway car; the combination of oppositely disposed framing elements, a metallic wall comprising two metallic plates secured together by a lap joint, said wall having an integral Z shaped member formed at one vertical margin thereof having each end secured to one of said framing elements, said member comprising a web and an outer flange, the overlapping relation of the webs and the outer flanges being greater than elsewhere, and means to secure said webs and outer flanges together.

2. In a railway car; the combination of oppositely disposed framing elements, a metallic wall comprising two metallic plates secured together by a lap joint, said wall having an integral Z shaped member formed at one vertical margin thereof having each end secured to one of said framing elements, said member comprising a web, an inner flange and an outer flange, the overlapping relation of the webs and the inner flanges and the outer flanges being greater than elsewhere, and means to secure said webs, inner flanges and outer flanges together.

3. In a railway car; the combination of oppositely disposed framing elements, a metallic wall comprising two metallic plates secured together by a lap joint along a horizontal line, said wall having an integral Z shaped member formed at one vertical margin thereof having each end secured to one of said framing elements, said member comprising a web and an outer flange, the overlapping relation of the webs and the outer flanges being greater than elsewhere, means to secure said webs and outer flanges together, and horizontally disposed corrugations formed in the plates and terminating therein adjacent said member.

4. In a railway car, the combination of oppositely disposed framing elements, a metallic wall comprising two metallic plates secured together by a lap joint, said wall having an integral Z shaped member formed at one vertical margin thereof having each end secured to one of said framing elements, the overlapping relation of said member being greater than elsewhere.

5. In a railway car, the combination of oppositely disposed framing elements, a metallic wall comprising two metallic plates secured together by a lap joint, said wall having an integral Z shaped member formed at one

vertical margin thereof having each end secured to one of said framing elements, the overlapping relation of said member and a portion of the end wall adjacent said member being greater than elsewhere.
